MIXING MACHINE FOR JUGS OR SIMILAR ARTICLES

Thaddeus E. Bednarski, Sterling, Ill., Clarence E. Norton,
Cedar Rapids, Iowa, and Warren P. Wahl, Sterling, Ill.,
assignors to Wahl Clipper Corporation, Sterling, Ill.,
a corporation of Illinois

Filed Oct. 29, 1963, Ser. No. 77,189

Term of patent 14 years

(Cl. D55—1)

FIG. 1 is a front perspective view, looking from the upper left, of a mixing machine for jugs or similar articles embodying our new design.

FIG. 2 is a rear perspective view, looking from the upper left, thereof.

The broken line showing of the jug in FIG. 1 is for illustrative purposes only.

The dominant features of our new design are shown in full line.

We claim:

The ornamental design for a mixing machine for jugs or similar articles, as shown and described.
